PUMP UNIT

William L. Dunn, Charlotte, and Fred C. Rankin,
Stanley, N. C.

Application March 7, 1941, Serial No. 382,118

4 Claims. (Cl. 103—3)

This invention relates to pumps and more specifically to one of the reversible centrifugal type.

It is an object of this invention to provide reversing pump units comprising an outer casing having a pair of openings therein, which casing has a centrifugal pump with a pump housing mounted therein, the outlet port of which is adapted to communicate with either of said openings and the inlet port of which is adapted to communicate with the opening, not communicating with the outlet port. This type of structure makes it possible to easily reverse the direction of flow through the outer housing by shifting the outlet port of the centrifugal pump housing relative to the openings.

It is another object of this invention to provide a reversing unit as above described in combination with a yarn kier circulating system wherein the ports in the casing are so connected that the fluid in the system can be circulated and recirculated in either direction through the yarn within the kier.

It is another object of this invention to provide a circulating system constructed substantially as follows: A conduit having a yarn kier interposed therein has the ends thereof leading into a casing in which a centrifugal pump housing is rotatably mounted. The outlet of the pump housing may be caused to coincide with either end of said conduit while the other end of the conduit communicates with the inlet port of the pump housing. Also communicating with the pump inlet port is a fluid supply such as an expansion tank, and leading from the outer casing is a drain valve. When it is desired to draw fluid from the tank and direct it through the kier in either direction to the drain valve, it is only necessary to open the valve and then rotate the centrifugal pump housing to cause the outlet of the pump housing to communicate with the desired end of the conduit. The last-named operation is commonly called the running wash wherein the dye liquor is expelled from the circulating system and another fluid from the expansion tank is directed first in one direction and then in another through the yarn kier as it flows to the drain.

It is another object of this invention to provide a circulating system as above described in which the fluid upon its return into the outer casing as it travels to the drain valve is conducted along a path which leads below the eye of the impeller or inlet of the centrifugal pump housing. During the running wash, the head at the eye of the impeller is maintained substantially at zero by the

inflow of water from the expansion tank. By returning the fluid from the yarn kier below the eye of the impeller there will be no tendency for it to be drawn again into the inlet of the pump housing, because a negative head would be required. In other words, during the running wash, the circulating dye fluid is immediately expelled through the drain valve and is followed by another fluid which is drawn from the expansion tank.

10 Practically none of the same fluid re-enters the impeller housing to be recirculated.

It is another object of this invention to provide a circulating system of the class described in which a baffle plate is mounted in the lower portion 15 of the expansion tank and above the opening therein whereby vortices will be prevented from forming and air will not be permitted to enter the system. Air not only causes bubbles to form in yarn packages being dyed and thus 20 prevents even distribution of the dye, but it is also very injurious to certain types of dyes, and often causes oxidation, resulting in poor dyeing. The baffle, not only serves to prevent air from entering the system, but also serves to counteract disturbance of the liquid in the tank due to "coughing" or escape of air, should air by any chance get into the system.

It is another object of this invention to provide a cooling and heating system for yarn kiers, 30 comprising a jacket disposed around the kier and having two compartments therein, one for circulation of a heating agent such as steam and the like and the other for the circulation of a cooling agent such as water.

35 Some of the objects of the invention having been stated, other objects will appear as the description proceeds, when taken in connection with the accompanying drawings, in which—

Figure 1 is an elevation with certain portions 40 thereof shown in section, illustrating an improved pump unit as applied to a yarn circulating system;

Figure 2 is a plan view showing certain portions in section and omitting other portions of 45 Figure 1;

Figure 3 is a vertical transverse sectional view taken along the line 3—3 in Figure 1;

Figure 4 is an elevation of the pump unit detached from its associated parts, said view being 50 taken along the line 4—4 in Figure 2;

Figure 5 is an enlarged vertical sectional view through the pump along the line 5—5 in Figure 2;

Figure 6 is a sectional detail plan view taken along the line 6—6 in Figure 5;

55 Figure 7 is a sectional plan view through the

pump unit showing the interior thereof in elevation, said view being similar to the central portion of Figure 2;

Figure 8 is a vertical sectional view taken along the line 8—8 in Figure 2, showing the opposite side of the pump unit from that illustrated in Figure 4.

Referring more particularly to the drawings, the numeral 18 denotes a suitable base upon which a yarn kier 11 is mounted, said yarn kier having a package holder 12 on the interior thereof (Figure 3) which has upstanding perforated tubes 14. Around each of these tubes, a plurality of packages of yarn 15 are mounted. The kier is provided with a suitable cover 16 which is pivoted as at 17 to arms 18, said arms being pivoted intermediate their ends as at 19, and having a counterweight 20 on the other ends which facilitates the opening and closing of the lid 16. Suitable bolts 21 and nuts 22 are employed for clamping the cover 16 in a tight position over the upper portion of the yarn kier 11.

Leading from the upper portion of the cover or lid 16 is a vent and feed pipe 26 which pipe has its other end leading to a point above an expansion tank 27. A suitable valve 28 is disposed in the pipe 26, which valve is manipulated when it is desired to vent the upper portion of kier 11, or when it is desired to permit some of the dye liquor within the kier to drain therefrom into the expansion tank 27.

The bottom portion of the yarn kier 11 (Figure 3) has pipes 29 and 30 leading therefrom, the pipe 29 being adapted to communicate with the exterior of the packages of yarn on the package holder 12, and the pipe 30 being adapted to communicate with the interior of the packages. The openings in suitable pipes 31 and 32 are adapted to coincide with the openings in pipes 29 and 30 respectively, said pipes 31 and 32 leading into a stationary outer casing broadly designated by the reference character 33. By referring to Figure 5, it is seen that the outer casing 33 comprises two parts, namely, casing 34 and casing cover 35, said members 34 and 35 being removably secured together by means of suitable bolts 36. The casing parts 34 and 35 are shouldered as at 37 and 38 respectively, thereby forming a peripheral trackway over which flanges 40 and 41 of an impeller housing 42 is adapted to slidably fit. An impeller shaft 44 is the axis about which housing 42 rotates although it is not directly connected thereto. Also the impeller housing 42 has an outlet pipe 45 the end of which is adapted to snugly slide against the interior periphery 57 of the casing 34 to be rotated so that the outlet therein will coincide with either the openings in pipes 31 or 32, depending upon the direction of circulation of the fluid desired in the circulating system. The means for rotating the impeller housing will be described later.

This impeller housing 42 has an impeller 46 rotatably mounted therein, and fixedly secured on the end of shaft 44 previously described. It is seen that the impeller has a plurality of outwardly extending vanes 47 which are spaced apart so as to form openings 48 through which the fluid is adapted to pass during normal operation of the pump. This impeller has annular flanges 50 and 51 which rotatably fit against annular shoulders 52 and 53 of members 34 and 35 respectively, thereby providing a close fit and preventing escape of a fluid from the interior of the impeller housing 42 except by way of openings 48.

The impeller 46 has an inlet opening or an eye 55 through which the liquid enters during the operation of the pump. This eye communicates with an enlarged arcuate space 57a in the cover 35 said space being formed by an outwardly projecting blister 56 on the cover. The space 57a also communicates with one of the pipes 31 or 32, depending upon the position that the outlet port of the impeller housing occupies. With the outlet pipe 45 in the position shown in Figure 3, the eye of the impeller 55 has communication with the outlet 31 by way of space 57a; whereas if the outlet pipe 45 should be communicating with the upper pipe 31, the eye 55 would communicate with lower pipe 32 by way of space 57a. The outlet pipe 45 has a flange portion 45a which slidably fits against arcuate surface 57 on the interior of housing 34.

In order to turn the outlet pipe 45 of the impeller housing 42 from one position to the other, within the casing 33, a suitable arcuate rack 60 has been provided on the outer periphery of the impeller housing (Figures 3 and 7). This rack is adapted to mesh with a pinion 61, said pinion being disposed on the interior of outer casing 34 and fixedly secured around a shaft 62. By observing Figures 1, 2, 7 and 8, it will be seen that the shaft 62 extends to the exterior of the casing and has a beveled gear 63 on the end thereof, which gear meshes with another beveled gear 64 on the lower end of a vertically disposed operating shaft 65. The operating shaft 65 extends upwardly above a floor 66 and through a stand 67. Upon the upper end of the shaft 65, a suitable operating handle 68 is secured. This operating handle is manipulated to rotate the shaft 65 when it is desired to turn the impeller housing 42 and the associated outlet pipe 45 within casing 33.

When the parts are in the position shown in Figure 3, and the system is filled with a suitable circulating fluid such as dye liquor, the fluid is drawn into the impeller housing by way of opening or eye 55 and expelled through the openings 48 between vanes 47. Then the liquid passes out of pipe 45, through pipes 32, 30 and up on the interior of perforated pipes of package carrier 12. From this stand, the fluid passes upwardly through perforated tubes 14 and then out through the packages of yarn 15, from whence it is permitted to circulate downwardly on the exterior of the stand 12, through pipes 29 and 31 and into space 57a after which it returns to the eye 55 for recirculation.

Particular attention is called to the fact that the dye solution, after leaving the yarn kier, returns to the casing 33 and is directed to a position below the eye 55 before it is permitted to again enter the impeller eye. This is a very valuable feature in the running wash operation which will subsequently be described. When it is desired to reverse the direction of flow from that previously described, it is only necessary to manipulate the handle 68 and thereby rotate the impeller housing 42 to a position where the outlet pipe 45 will communicate with opening 31. When in this position, the fluid will be forced from the impeller casing through pipes 31 and 29, through packages 15 into the interior of the perforated tubes 14 and into the manifold 12a of package carriage 12. From the inside of the manifold, the circulating fluid will pass through pipes 30 and 32 and into space 57a.

In order to drive the impeller shaft 44, a suitable motor 69 is provided. This motor has a shaft

70 extending therefrom and is joined to the shaft 44 by means of a suitable coupling 71. The shaft 44 is supported by a suitable bracket 72, said bracket resting upon suitable I-beams 74. One end of bracket 72 has a flange portion 73 to which is secured the casing 34 by any suitable means such as bolts 73a. The I-beams 74 also support the motor 69.

The casing cover 35 has a port 80 over which the lower end of a pipe 81 is adapted to fit, said pipe having a check valve 82 therein. The upper portion of the pipe 81 is connected to the lower portion of the expansion tank 27. Also leading from the outer casing 33 is a pipe 84 to which is connected a drain valve 85. After the dye liquor in the circulating system has been circulated and recirculated through the packages of yarn the desired length of time, it is often desired to drain the liquor from the system and to wash the yarn with another fluid before finally removing it from the kier. In order to do this, it is necessary to open the drain valve 85 so that the liquor or fluid in the circulating system will be permitted to escape and at the same time other fluid from the expansion tank 27 will be permitted to move downwardly through opening 89 and into eye 55 of the impeller 46 from whence it will be expelled therefrom through port 45 and into one of the openings 31 or 32. The fluid will then be circulated in one direction or the other through the yarn kier, but regardless of the direction in which it is circulated, it will be returned to the casing 33 along a path of flow which is disposed below the eye 55.

As previously pointed out, the head at the impeller eye is substantially zero when the running wash is being employed due to the flow of fluid from the expansion tank 27 into opening 55. Therefore, since it would require a negative head to pull the returning fluid upwardly back into the eye and recirculate it through the pump and kier, the fluid will immediately flow out through the drain valve 85 instead.

This drain valve 85 has a closure member 90 mounted therein which is disposed on the lower end of a shaft 91, said shaft extending upwardly (Figure 1) through floor 66 and through a stand 92. The upper end of the shaft has an operating wheel 93 thereon which is turned when it is desired to open or close the valve 85.

The upper portion of the impeller housing 42 has a vent hole 100 therein which permits the air within the pump to escape to the upper portion of the outer casing 33. From the upper portion of the outer casing, the air moves upwardly through vent pipe 102, valve 103, and is expelled into the expansion tank 27. Of course where there is liquid mixed with the air, the surplus liquid will fall back into the expansion tank 27.

It is very essential that vortices be prevented from forming in the expansion tank 27 because air in the circulating system is very often injurious to certain dyes on account of oxidation. In order to prevent vortices from forming, a suitable circular baffle plate 110 is mounted in spaced relation to the bottom of the expansion tank 27 and directly above the opening in pipe 81, which leads to the pump unit. This plate not only prevents air from entering the circulating system but should some air inadvertently get into the system and have a tendency to spit or backfire it will serve to retard the disturbance of fluid in the tank which would occur when this backfire occurs. This backfire is commonly called "coughing" because the air in the system is find-

ing an outlet through the expansion tank. As an additional means for preventing vortices in the circulating system, a suitable blade 105 is secured across the impeller opening 55 (Figures 5 and 6).

The yarn kier is very often made of stainless steel in order to prevent rust. The low heat conductivity of stainless steel often makes it necessary to provide a cooling system for the yarn kier because there is an increased heat due to the circulation and recirculation of the fluid, during normal operation. Also kiers are often made of cast iron, having a high conductivity and also having a greater radiation thereby making it necessary to add heat so that the circulation system will be kept at the proper temperature, a temperature which ranges sometimes as low as 110 degrees Fahrenheit. Of course, when stainless steel is used and a very high dye temperature is used, e. g., 200 degrees Fahrenheit, it is often necessary to add heat to the kier during normal operations, but these are exceptional cases.

Heretofore, in some instances, a single jacket 25 has been used around the kier through which steam or other heating agent was circulated when it was desired to heat the yarn kier. A suitable cooling agent such as water was introduced in this same jacket when it was desired 30 to cool the same. This has been unsatisfactory. Where only one compartment was employed for both water and steam it was necessary to provide a steam trap in the outlet pipe to collect condensate. When the cooling was necessary the 35 steam must be exhausted and water admitted into the jacket. The steam trap ordinarily provided is not large enough to permit the water to flow fast enough from the jacket to give the proper cooling circulation.

40 This difficulty has been overcome in the present invention by providing jacket 112 having two compartments 113 and 114 therein, extending entirely around the kier. The compartment 113 is used for circulating the water and has an inlet pipe 116 with a valve 117 therein. The water flows from compartment 113 by way of pipe 115. The lower compartment 114 is used for steam and has an outlet pipe 118 with a valve 119 therein and also has an outlet pipe 120 having a condensation trap 121 therein. The two compartments can be used independently, therefore no difficulty will arise so far as quick cooling or heating is concerned.

55 When the circulating system is first charged, it is necessary to heat the fluid to an initial starting temperature. This initial temperature is provided by admitting steam into the pump casing by way of a pipe 125, said pipe having a valve 126 therein. A perforated strainer or grill 127 60 serves to reduce the noise of the steam as it is admitted.

When the pump is connected to a dyeing kier 112, as shown in Figures 1 and 2, the dyeing kier is completely full of liquid and all pipes including the pump are also full of liquid. The expansion tank is also partially filled with the liquid, as well as its pipe leading to the pump. Therefore, even though there is an intake port leading from the kier into the pump and an intake port 70 leading from the expansion tank into the pump, no liquid can flow from the expansion tank into the pump unless the kier should not be completely filled with liquid. As the liquid expands in the kier, it passes through pipe 26 into the 75 expansion tank, but in any event, the intake

port from the kier will have suction applied thereto by the pump for the reason that the kier being full, there will be no passage of liquid from the expansion tank into the pump, because there will be no room for it in the kier.

In the drawings and specification, there has been set forth a preferred embodiment of the invention, and although specific terms are employed they are in a generic and descriptive sense only and not for purposes of limitation, the scope of the invention being set forth in the following claims.

We claim:

1. A reversible centrifugal pump comprising an outer casing having two ports, a movable pump casing rotatably mounted in the outer casing and having a centrifugal pump therein, the inner casing having an outlet port along its periphery and having an inlet opening along its axis of rotation, means for selectively moving the inner casing so as to cause its outlet port to register with either of the ports of the outer casing, the inner casing having a sliding water-sealed fit with the walls of the outer casing, the outer casing having an enlargement on one side thereof of forming a passageway disposed alongside both ports of the outer casing and being in communication with one of the two ports in the outer casing at all times, whereby liquid entering the outer casing through either of the ports of the outer casing will pass along and outside of the inner casing to the lower part of the outer casing, and said lower part of the outer casing including said enlarged passageway having communication with the inlet port of the inner casing.

2. A reversible centrifugal pump comprising an outer casing having two ports, a movable pump casing rotatably mounted in the outer casing and having a centrifugal pump therein, the inner casing having an outlet port along its periphery and having an inlet opening along its axis of rotation, means for selectively moving the inner casing so as to cause its outlet port to register with either of the ports of the outer casing, the inner casing having a sliding water-sealed fit with the walls of the outer casing, the outer casing having an enlargement on one side thereof of forming a passageway disposed alongside both ports of the outer casing and being in communication with one of the two ports in the outer casing at all times, whereby liquid entering the outer casing from either of the ports of the outer

casing will pass along and outside of the inner casing to the lower part of the outer casing, and said lower part of outer casing including said enlarged passageway having communication with

5 the inlet port of the inner casing, said outer casing having a third port for receiving liquid and having communication with the inlet port of the inner casing and having a deflecting lip associated therewith for directing incoming liquid 10 from the third port directly into the intake opening of the inner casing.

3. A pump having an outer casing provided with four openings therein comprising an intake opening and a discharge opening and a pair of 15 other openings, a centrifugal pump mounted within the outer casing and having an inner casing provided with an axially disposed intake opening mounted for rotation about the axis of the pump and the inner casing having an extension 20 provided with a discharge opening adapted to register with either of the two openings which are adapted to be connected to a circulatory system, one side of the outer casing having an enlargement extending alongside and communicable 25 with one of said two openings at a time, said enlargement then extending further downwardly and then upwardly to a point opposite said axially disposed intake opening, whereby new fluid may be conducted into the inner pump casing and the old fluid may be discharged through 30 the discharge opening.

4. A centrifugal pump comprising inner and outer casings, the outer casing having a pair of 35 openings and the inner casing having a peripheral opening and being adapted to rotate about the axis of the centrifugal pump and having an opening surrounding said axis, an enlargement on one side of the outer casing extending past 40 said two openings and communicable therewith one at a time to the lower part of the casing and then extending upwardly and communicating with the opening surrounding the axis of the centrifugal pump, the outer casing also having an intake opening for new fluid and a discharge 45 opening whereby incoming fluid from one of the pair of openings will be directed to the bottom of the outer casing and up through the centrifugal pump and exhausted from the centrifugal pump through the other of said pair of openings 50 and whereby old fluid may be discharged directly out of the discharge opening of the outer casing.

WILLIAM L. DUNN.

FRED C. RANKIN.
